[57] CLAIM

The ornamental design for a snow sled, as shown and described.

DESCRIPTION

FIG. 1 is a perspective view of a snow sled showing my new design;

FIG. 2 is a top plan view thereof;

FIG. 3 is a side elevation view thereof;

FIG. 4 is a bottom plan view thereof;

FIG. 5 is a rear elevational view thereof;

FIG. 6 is a front elevational view thereof; and

FIG. 7 is a fragmentary portion of the side elevation view on a greatly enlarged scale of the area within the circled region 7 of FIG. 3.
